(57) **CLAIM**

The ornamental design for a cell phone holster, as shown and described.

DESCRIPTION

FIG. 1 is a front isometric view of the cell phone holster, which embodies my design;

FIG. 2 is a rear isometric view of the cell phone holster;

FIG. 3 is a front view of the cell phone holster;

FIG. 4 is a rear view of the cell phone holster;

FIG. 5 is a top view of the cell phone holster;

FIG. 6 is a bottom view of the cell phone holster;

FIG. 7 is a right side view of the cell phone holster;

FIG. 8 is a left side view of the cell phone holster;

FIG. 9 is an illustrative view of a cell phone holster showing my new design in a position of use. The broken line showing of a cell phone in FIG. 9 is for illustrative purposes only and forms no part of the claimed design; and,

FIG. 10 is an illustrative view of a cell phone holster showing my new design in a position of use. The broken line showing of a belt in FIG. 10 is for illustrative purposes only and forms no part of the claimed design.
